PORTABLE COLD BEER DISPENSER

Charles O. Marx, Baldwin, N. Y.

Application February 13, 1935, Serial No. 6,295

7 Claims. (Cl. 225—16)

This invention relates to new and useful improvements in a portable cold beer and beverage dispenser.

- The invention relates to a device provided with a plug engageable in the bung hole in the top of a beer barrel or other beverage keg, and associated with a vertical pipe extending through the plug for engaging into the beverage, and connected with a cooling coil, and mechanism for the discharge of air into the barrel to provide pressure for the dispensing of the beverage. Combinations of this type are generally known, this invention applying to novel features in the combination.
- 15 The invention has for an object the construction of an article as mentioned which is characterized by the fact that the plug is of hollow construction and slidably and adjustably arranged upon the vertical pipe and associated in such a manner with an air supplying mechanism that adjustments of the position of the plug on the pipe are possible without interfering with the operation of the device. The feature of this arrangement is that the apparatus may readily be 20 adjusted to barrels of different heights.

A further object of this invention is to construct the device in such a manner that an air pump operated with a vertical stroke of a handle is arranged coaxially with said vertical pipe so as to be in a firmly supported position. In prior constructions the hand pumps were offset and connected with the coils of the device or in other positions in which they were not rigidly supported which did not produce a compact solid unit as taught by this invention.

35 A further object of this invention is the association of a container for ice or other refrigerant, with the coil previously mentioned, and the construction of the parts in such a manner that the hand pump is located centrally of the container.

Still further the invention proposes the construction of an article as mentioned which is simple and durable and which can be manufactured 40 and sold at a reasonable cost.

45 For further comprehension of the invention, and of the objects and advantages thereof, reference will be had to the following description and accompanying drawing, and to the appended 50 claims in which the various novel features of the invention are more particularly set forth.

In the accompanying drawing forming a material part of this disclosure:—

55 Fig. 1 is a side elevational view of a device constructed according to this invention.

Fig. 2 is a fragmentary enlarged transverse sectional view of a portion of Fig. 1.

Fig. 3 is an elevational view looking in the direction of the line 3—3 of Fig. 1.

The portable cold beer and beverage dispenser, 5 according to this invention, comprises a vertical pipe 10 for extension into the beer 11 of a beer barrel 12 (illustrated fragmentarily). A cooling and dispensing device is supported on the top of the vertical pipe 10 and is connected therewith. 10 This cooling and dispensing device comprises a container 13 open at the top and equipped with a coil 14 arranged in such a manner that a refrigerant may be placed therein to cool liquid in the coil.

15 The coil 14 has a discharge end 14a connected with a faucet 15 mounted on the outer side of the container. The coil 14 has an inlet end 14b connected with a pipe 16 arranged through the bottom of the container and connecting with a bracket 17 attached upon the bottom of the container axially therewith. The bracket 17 is formed with a hollow portion 18 which is cut off from the pipe 16. The pipe 16 opens into a receiving portion 16a having an opening at the bottom connecting with the upper end of the pipe 10. The pipe 10 extends into the bottom of the bracket 17 and is secured with a rubber gasket 19 arranged in a recess in the bracket 17 and clamped into tight position with a gland arranged coaxially 20 upon the pipe 10 and threadedly engaging the outer end of the recess.

25 The air pump 21 is attached on the cooling and dispensing apparatus and is connected with the hollow portion 18 of the bracket 17. The details 25 of this pump will not be given since pumps of this type are generally known and form no part of this invention. To better understand the operation of the device it is stated that the pump 21 is provided with a handle 22 on the top which 30 may be moved vertically upwards and downwards to operate the pump. The pump has air inlets 23 at the top and a discharge 24 which extends through the bottom of the receptacle 13 and connects with the hollow portion 18. The bracket 35 17 is provided with an outlet 25 from the hollow portion 18.

30 A hollow plug 26 for engaging through the bung opening 27 of the beer barrel 12 is arranged coaxially on and adjustably fixed with the pipe 50 10. More particularly, the pipe 10 extends through a packing gasket 27 arranged in the top end of the plug and clamped into compressed condition with a plug 28 threadedly engaged in the recess in which the packing is disposed. The 55

hollow portion 29 of the plug surrounds the pipe 10 and discharges at the lower end of the plug completely around the pipe. The hollow portion 29 connects with a side inlet 30. A detachable hose 31 is engaged upon the outlet 25 and the inlet 30 to connect these parts.

The pipe 10 is formed from a lower pipe section 10a and an upper pipe section 10b connection together with a valve body 32 provided with a cock type of valve 33. The valve 33 controls the passage of the beer or beverage through the pipe 10. The bottom of the receptacle 13 is provided with an outlet 34 for the discharge of water or liquid in the event that the refrigerant is of the type that melts, such as ice.

The operation of the device is as follows: The plug 26 is adjusted upon the pipe 10 to a position so that when the plug is engaged in the bung hole in the top of a beer barrel, the pipe extends nearly to the bottom of the barrel. The hose 31 which is of flexible material such as rubber which allows adjustments; or a greater length of hose may be substituted therefor. After the device has been mounted upon the beer barrel the pump 21 is operated so that air is discharged into the hollow 18, down through the outlet 28, the pipe 31, the inlet 30 and the hollow 29 into the beer barrel. The pressure within the barrel therefore raises and the beer is forced up through the pipe 10, past the valve 33 when open, along the pipe 16 into the coil 14 and to the faucet 15. Refrigerant is then placed in the container 13 to cool the beer within the coil 14 and the cold beverage may be dispensed as desired.

It is a feature of this invention that the plug 26 is adjustable along the pipe 10 to change its position from the lower end. It is a further feature of this invention that the pump 21 is arranged coaxially with the bracket 17 which is arranged coaxially with the pipe 10 for forming a compact and solid unit. It should be recognized that the entire device is supported by the plug 26 supporting the pipe 10 and for this reason it is desirable that the pump be arranged axially. A further feature lies in the arrangement wherein the pump 21 is disposed within the receptacle 13 to reduce the compass of the device and to increase its rigidity.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

1. In a portable cold beer and beverage dispenser, a vertical pipe for extending into the beer of a beer barrel for the discharge of the beer, a cooling and dispensing device on top of said vertical pipe and connected therewith, an air pump attached on said cooling and dispensing device and extending through the bottom thereof and connected with a stationary hollow bracket beneath the said cooling and dispensing device formed with an air outlet, a hollow plug for engaging into the bung hole of the top of a beer barrel and adjustably fixed coaxially on said pipe and having an air inlet near the top and a discharge at the bottom around said pipe into said barrel, and a hose connecting said air outlet and air inlet.

2. In a portable cold beer and beverage dis-

penser, a vertical pipe for extending into the beer of a beer barrel for the discharge of the beer, a cooling and dispensing device on top of said vertical pipe and connected therewith and including a container, an air pump attached on said cooling and dispensing device within said container and extending through the bottom thereof and connected with a stationary hollow bracket formed with an air outlet, a hollow plug for engaging into the bung hole of the top of a beer barrel and adjustably fixed coaxially on said pipe and having an air inlet near the top and a discharge at the bottom around said pipe into said barrel, and a hose connecting said air outlet and air inlet, said vertical pipe being made from pipe sections connected with a valve for the control of the passage of the beverage.

3. In a portable cold beer and beverage dispenser, a vertical pipe for extending into the beer of a beer barrel for the discharge of the beer, a cooling and dispensing device on top of said vertical pipe and connected therewith, an air pump attached on said cooling and dispensing device and connected with a stationary hollow bracket formed with an air outlet, a hollow plug for engaging into the bung hole of the top of a beer barrel and adjustably fixed coaxially on said pipe and having an air inlet near the top and a discharge at the bottom around said pipe into said barrel, and a hose connecting said air outlet and air inlet, said cooling and dispensing device comprising a receptacle provided with a coil connected at one end with a discharge faucet and at the other end with a pipe line connecting with said stationary hollow bracket and discharging into the top of said pipe and said air pump being located within said receptacle and extending through the bottom thereof to connect with said hollow bracket.

4. In a portable cold beer and beverage dispenser, a vertical pipe for extending into the beer of a beer barrel for the discharge of the beer, a cooling and dispensing device on top of said vertical pipe and connected therewith, an air pump attached on said cooling and dispensing device, and connected with a stationary hollow bracket formed with an air outlet, a hollow plug for engaging into the bung hole of the top of a beer barrel and adjustably fixed coaxially on said pipe and having an air inlet near the top and a discharge at the bottom around said pipe into said barrel, and a hose connecting said air outlet and air inlet, said air pump having a discharge extending through the bottom of a container included in said cooling and dispensing device and connected with the hollow of said hollow bracket.

5. In a portable cold beer and beverage dispenser a vertical pipe for extending into the beer of a beer barrel for the discharge of the beer, a cooling and dispensing device on top of said vertical pipe and connected therewith, an air pump attached on said cooling and dispensing device and connected with a stationary hollow bracket formed with an air outlet, a hollow plug for engaging into the bung hole of the top of a beer barrel and adjustably fixed coaxially on said pipe and having an air inlet near the top and a discharge at the bottom around said pipe into said barrel, and a hose connecting said air outlet and air inlet, said cooling and dispensing device including a container open at its top, a beer coil around the walls of said container so that a refrigerant may be placed therein, a faucet connected with one end of said beer coil, and the other end of said beer coil being connected with the side of said hollow bracket and connecting

with the top of said vertical pipe, said pump being mounted within said container and extending through the bottom thereof and connecting with said hollow bracket.

5. 6. In a portable cold beer and beverage dispenser a vertical pipe for extending into the beer of a beer barrel for the discharge of the beer, a cooling and dispensing device on top of said vertical pipe and connected therewith, an air pump attached on said cooling and dispensing device and connected with a stationary hollow bracket formed with an air outlet, a hollow plug for engaging into the bung hole of the top of a beer barrel and adjustably fixed coaxially on said pipe and having an air inlet near the top and a discharge at the bottom around said pipe into said barrel, and a hose connecting said air outlet and air inlet, said hollow bracket comprising a cylindrical shaped bracket attached upon the bottom of a container included in said cooling and dispensing device and arranged coaxially with said pipe.

7. In a device of the class described, a cooling

and dispensing device including a container open at its top, a hollow cylindrical top bracket attached on the bottom of said container and having an air outlet, an air pump mounted within said container and extended through the bottom and having its discharge connected with the hollow of said bracket, a vertical pipe coaxially attached with the bottom of said bracket to support the cooling and dispensing device, said vertical pipe being for the purpose of extending into the beer of a beer barrel, a pipe line from the side of the top bracket for delivering liquid from the top of said vertical pipe to said cooling and dispensing device, a hollow plug for engaging into the bung hole of the top of a beer barrel and adjustably fixed coaxially on said vertical pipe and having an air inlet near the top and a discharge at the bottom around said pipe into the barrel, and a detachable hose connecting said air outlet and said air inlet.
